United States Patent Office

Des. 184,866
Patented Apr. 14, 1959

184,866

COMBINED PAD AND HOLDER THEREFOR

Richard B. Gassaway, Houston, Tex.

Application October 29, 1957, Serial No. 48,263

Term of patent 14 years

(Cl. D74—1)

Fig. 1 is a front elevational view of a combined pad and holder therefor showing my new design;

Fig. 2 is a side view thereof; and

Fig. 3 is a bottom view thereof.

I claim:

The ornamental design for a combined pad and holder therefore, as shown.
